BLANK CUTTING AND CREEASING MACHINE

Linwood Wismer, Audubon, N. J., assignor to
Louis Wolf, Howard A. Wolf, and Elias Wolf,
copartners doing business as National Metal
Edge Box Company, Philadelphia, Pa.

Application January 5, 1932, Serial No. 584,762

7 Claims. (Cl. 164—62)

This invention relates to a blank cutting and creasing machine and more specifically to a machine in which a large blank may be cut by rectangular intersecting cuts into smaller blanks which are further creased in the desired fashion.

In blank cutting and creasing machines heretofore in use, it has been customary to move the large blank or sheet in one direction creasing and cutting a portion of the sheet and thereafter moving the cut and creased portions at right angles to the original direction of feed to not only crease but also cut the blank into smaller blanks suitable for the formation of a box or lid.

It is a broad object of the present invention to provide a machine in which cutting of an entire sheet may be effected in both movements so that more blanks may be formed from the original sheet. Specifically this is effected by so controlling the blanks after initial severing so that they will feed properly to the next set of cutters and creasers. Numerous other objects relating particularly to details of construction will be apparent from the following description read in conjunction with the accompanying drawings in which:

Fig. 1 is a plan view of the improved machine;

Fig. 2 is a front elevation thereof, certain parts being in section;

Fig. 3 is a side elevation of the machine viewed in the direction of the arrow 3 in Fig. 1;

Fig. 4 is a longitudinal section of the machine taken at right angles to the axis of the first cutting and creasing shafts;

Fig. 5 is a section taken on the plane indicated by 5—5 in Fig. 1, illustrating certain parts of the machine; and

Fig. 6 is a diagrammatic view of the original blank showing the cuts and creases formed therein in the embodiment of the invention illustrated.

The machine comprises a supply table 2 and a supporting table 4. The large blanks are carried on the supply table 2 in the form of a stack 6 from which they are fed from the top of the stack toward the first cutters and creasers. Guide fingers 8 illustrated in Fig. 2 serve to direct the feed blanks downwardly into proper position to be seized by the initial rollers. In order that the blanks may be entered between the rollers only at the proper time, a stop 10 is provided in the form of a vertically reciprocating slide mounted in guides 12 and provided with sidewise extending pins 14 between which

engages the turned end of a shaft 16, the opposite turned end of which engages a cam 18 mounted on a continuously rotating shaft 20. Normally, the operator who is feeding the blanks will press a blank towards the first rollers. Movement in that direction, however, will be limited by the stop 10 until the proper time occurs for insertion of the blank between the rollers. At this time the cam 18 rocks the stop 10 downwardly so that the blank may be moved inwardly.

Power is delivered to the machine through a pulley 22 which is carried by the shaft of a built-up drum 24 which may be of the usual type, having suitable knives 26 and creasers 28 carried thereon. In the present instance there are not only the edge trimming knives 26 but also there is an intermediate knife 26 designed to cut the blank into two parts. The knives 26 cooperate with similar knives 27 carried by the lower cooperating roller 25. Similarly cooperating creaser elements are carried by this lower roller. Suitable gearing connects the two rollers so that they will rotate in proper relationship to each other.

Through beveled gearing 30 rotation is imparted to another pair of rollers 32 and 33 which, likewise, carry knives 34 and 35 and creasing elements 36 and 37. Here again there is an intermediate knife provided for cutting the blank at right angles to the original central cut. It will be understood, however, that several knives may be provided to form a corresponding number of blanks.

Gears 38 connect the two rollers for trimming or cutting and creasing movements while a train of gears 40 serves to drive the shaft 20 at the proper rate of speed to actuate the moving blanks.

Mounted on the inner end of the shaft 20 is a crank disc 42 which carries a radially adjustable crank pin 44 connected by a link 46 to a lever 48 pivoted to a fixed part of the machine at its lower end and connected by a link 50 to a depending ear 52 on a slide 54 mounted for horizontal sliding movements in suitable guides 56. The slide 54 carries a movable gauge 58 which, as most clearly illustrated in Fig. 1, has a forward pushing edge parallel to the axis of the second rollers. Its rear end is tapered downwardly towards the table 4, as indicated in Fig. 5.

Mounted above the table 4 is a suitable framework 60 which supports a number of elements designed to secure the proper relationship of the blanks. One of these comprises an angle-iron 62 to which are secured rubber or flexible

fiber members 64 most clearly illustrated in Fig. 5. These flexible members are capable of yielding in a direction towards the second pair of feed rollers so that a blank may move in that direction but if movement of a blank in the opposite direction tends to occur the members press downwardly and grip the same preventing such movement. As will be clear, hereafter, this feature is of utility inasmuch as the gauge 58 may be moving rearwardly beneath a blank. To prevent movement of the blank therewith the flexible members are provided.

Pressers 66 are provided to hold the blanks upon the table 4. These members which are beveled upwardly at their edges are carried by posts 68 secured in blocks 70 pivoted on horizontal rods 72. As will be obvious from Fig. 1, if a blank is moving towards the left in that figure the pressers 66 will readily rock upwardly to permit the blank to move therebelow. Brushes 74 of the type usually used also tend to hold the blanks upon the table.

To limit the inward movement of the blanks there is provided a stop 76 adjustable along a rod 78 which is pivoted in the frame 60. An arm 80 attached to its free end is connected by a pin and slot connection with the upper end of a lever 82 pivoted to the frame and arranged so that its downwardly extending end is engageable by a cam 84 in contact with which it is held by a spring 85. The object of this arrangement is to provide for raising of the stop out of the path of the moving gauge 58 so that the gauge may slide below the same without impact. Suitable adjustment of stop 76 along the rod 78 provides for various sizes of blanks.

Directly beyond the rollers 24 and 25 are feed rollers 88 designed to engage the incoming blank which is separated into a plurality of pieces and direct the pieces into engagement with downwardly extending fingers 86 which project at leading ends of the blanks beneath the pressers and brushes. The rollers 88 are driven through suitable gearing 90 from the pulley 22.

Fig. 6 illustrates the original blank with the cut and crease lines thereon. The cut a is made by the central knives 26 and 27 on the rollers 24 and 25 while the cut b is made by the central knives 34 and 35 on rollers 32 and 33. While in the set-up disclosed only one series of central cutting knives is shown on rollers 24 and 25, it will be understood that a plurality of knives may be used to divide the blank into several separate blanks which are fed together upon the table 4. If there are more than two blanks a suitable number of guides 66 may be provided and the stop 76 may be extended to take care of all of the various sections approaching it. Of course, a plurality of stops may be provided if desired. Similarly, the cutting effected by the rollers 32 and 33 may take place so as to sub-divide the various sections into any desired number of finished blanks. Instead of forming merely four blanks, for example, sixteen or various intermediate numbers of blanks may be formed from a single feed.

In the operation of the machine, in view of the extended travel of the gauge 58, it must be such as to present the trailing blank to the rollers 32 and 33. The sections fed through the rollers 34 and 35 and 88 will ordinarily pass over the gauge 58 as illustrated in Fig. 5. As the gauge withdraws the members 64 prevent the sections from moving therewith thus holding their edges together so following sections do not ride up and over leading ones so that upon forward movement

of the gauge they push each other forwardly along the table. Proper alignment of their edges is insured by the pressers 66 acting together with the brushes 74.

It will be obvious that numerous variations in constructional details may be made without departing from the spirit of the invention as defined in the following claims.

What I claim and desire to protect by Letters Patent is:

1. A blank cutting and creasing machine including a table, means for cutting into sections blanks fed towards the table, means for cutting the sections so formed when moved from the table at an angle to their original movement and means for so moving the sections in succession from the table, said last means including a pusher having a range of movement sufficient to introduce the last trailing section to the second cutting means and means for continuously yieldingly holding the blanks downwardly upon the table and edge while being moved.

2. A blank cutting and creasing machine including a table, means for cutting into sections blanks fed towards the table, means for cutting the sections so formed when moved at an angle to their original movement, and means for so moving the sections in succession from the table, said last means including a pusher having a range of movement sufficient to introduce the last trailing section to the second cutting means and means for holding the blanks downwardly upon the table comprising pivoted pressers yieldable to readily permit movement of the sections on the table.

3. A blank cutting and creasing machine including a table, means for cutting into sections blanks fed towards the table, a stop for limiting movements of the sections, means for cutting the sections so formed when moved at an angle to their original movement, and means for so moving the sections in succession from the table, said last named means including a pusher having a range of movement sufficient to introduce the last trailing section to the second cutting means, and means for moving the stop from the path of the pusher.

4. A blank cutting and creasing machine including a table, means for cutting into sections blanks fed towards the table, means for cutting the sections so formed when moved at an angle to their original movement, and means for so moving the sections in succession from the table, said last means including a pusher having a range of movement sufficient to introduce the last trailing section to the second cutting means, and means for preventing movements of sections during retracting movements of the pusher.

5. A blank cutting and creasing machine including a table, means for cutting into sections blanks fed towards the table, means for preventing introduction of a blank to the said cutting means except at the proper time, means for cutting the sections so formed when moved at an angle to their original movement, and means for so moving the sections in succession from the table, the preventing means including a stop automatically controlled to release a blank at the proper time by a cam timed with respect to other parts of the mechanism.

6. A blank cutting and creasing machine including a table, means for cutting into sections blanks fed towards the table, means for cutting the sections so formed when moved from the table at an angle to their original movement,

means for so moving the sections in succession from the table, and means for continuously yieldingly holding the blanks downwardly along their abutting edges upon the table and edge to edge

5 while being moved.

7. A blank cutting and creasing machine including a table, means for cutting into sections blanks fed towards the table, means for cutting the sections so formed when moved at an angle

10 to their original movement, means for so moving the sections in succession from the table, said last

means including a pusher having a range of movement sufficient to introduce the last trailing section to the second cutting means, means for preventing movements of sections overlying the pusher during retracting movements of the 5 pusher, and means acting at certain times for preventing introduction of a blank to the first named cutting means but permitting the feeding of a blank to the first mentioned cutting means during the retracting movements of the pusher. 10

LINWOOD WISMER.
